HANGER SWING

Alfred J. Thomson, Detroit, Mich.

Application March 27, 1939, Serial No. 264,320

2 Claims. (Cl. 211—96)

My invention relates to hanger swings particularly designed for hanging, on swings, garment hangers.

A particular object is to provide a hanger swing which is so constructed that the swing arms, on which the garment hangers are hung, have hooks for the garment hangers arranged in a way to permit the garment hangers to hang parallel to the swing arms, and the arms have a normal tendency to swing towards a vertical wall on which the hanger swing is mounted.

An embodiment of the invention is shown in the appended drawing. In this drawing,

Fig. 1 shows the hanger swing;
Figs. 2, 3, 4, and 5 are views on corresponding lines of Figure 1 of the drawing.

The hanger swing hereof comprises a sheet metal base plate 10 having holes 11 whereby it may be secured to a vertical wall. The plate is formed to provide two vertically spaced horizontally projecting ledges 12—14, these being connected by a rounded tapering portion 15 of the plate, with the lower ledge 14 flanged, as at 16, for reinforcement.

Each ledge has an arcuate line or row of holes 17—18 formed for receiving hooked ends 19—20 of wire swing arms 21 on whose free ends 22 are straps or hooks 23 formed to permit conventional wire garment hangers 24 to hang from the arms and remain parallel to them.

The upper line of holes 17 is closer to the wall in back of plate 10 than the lower line of holes 18, and the holes of line 17 are farther apart than the holes of line 18, and the radius

of curvature of line 17 is greater than that of line 18; all this serves to produce in each swing arm a normal tendency to swing towards the vertical wall, and this tendency is greater with an increase in the load on hook 23.

5

I claim:

1. A hanger swing for garment hangers or the like comprising a base plate adapted to be secured to a vertical wall and having vertically spaced horizontally projecting ledges, each having an arcuate line of holes, and swing arms, each having a part seated in a hole of the upper line and a part seated in a hole of the lower line, the free part of each arm having a garment hanging hook formed to permit a garment hanger to hang parallel to the arm, the lower line of holes being farther out from the wall than the upper line and the holes of the lower line being closer to one another than those of the upper line, whereby each arm has a normal tendency to swing towards the vertical wall.

10

2. A hanger swing for garment hangers or the like comprising a base plate adapted to be secured to a vertical wall and having vertically spaced horizontally projecting ledges, each having an arcuate line of holes, and swing arms, each having a part seated in a hole of the upper line and a part seated in a hole of the lower line, the lower line of holes being farther out from the wall than the upper line and the holes of the lower line being closer to one another than those of the upper line, whereby each arm has a normal tendency to swing towards the vertical wall.
